To all whom it may concern:

Be it known that I, ARTHUR L. HALLIDAY, of Yonkers, in the county of Westchester and State of New York, temporarily residing at 5 present in Halifax, England, have invented and produced a new and original Design for a Carpet, of which the following is a full description, in connection with the accompanying photograph, which represents a face view 10 of my new design for a carpet.

This invention relates to a new ornamentation of the face of a carpet, oil-cloth, or analogous fabric.

In the accompanying photograph are represented the various parts which enter into 15 my new design.

A is a large central bouquet of flowers, near which is a smaller bouquet, B, from which fern-like leaves radiate, and below that is another bouquet, C, that adjoins a group of 20 leaves, D. Above the figure A is a group of strikingly-shaded leaves, E, which connects the figure A with the figures D and C above it.

I claim—
